(57) **CLAIM**

The ornamental design for an electronic display device mountable to a vehicle, as shown and described.

DESCRIPTION

FIG. 1 is a perspective view of the electronic display device mountable to a vehicle, showing our new design;

FIG. 2 is a front view thereof;

FIG. 3 is a rear view thereof;

FIGS. 4 and 5 are opposing side views thereof;

FIG. 6 is a top view thereof; and,

FIG. 7 is a bottom view thereof.

The broken lines illustrate unclaimed portions of the electronic display device mountable to a vehicle and form no part of the claimed design.

1 Claim, 3 Drawing Sheets
